(57) CLAIM

The ornamental design for a shoe as shown and described.

DESCRIPTION

FIG. 1 is a front perspective view of a shoe showing my new design;
FIG. 2 is a side view thereof; and,

FIG. 3 is a rear perspective view thereof.

The broken line showings of the six smaller triangular regions and the one larger triangular region within the shaded area form no part of the claimed design. The broken lines depicting the remainder of the shoe form no part of the claimed design.
